UNITED STATES PATENT OFFICE

2,186,801

SPOUTING SYSTEM FOR TYPE CASTING MACHINES

George L. Curle, Minneapolis, Minn.

Application March 24, 1938, Serial No. 197,820

10 Claims. (Cl. 199—59)

My present invention relates to type casting machines, and more particularly to the embodiment of a spouting system therein for collecting and conveying to a receptacle waste metal such as molten metal, that escapes during casting operations or that is spilled from the melting pot, shavings cut from type bars by trimming knives, dust and waste material cut from type bars by a sawing device on the machine, discarded type bars and the like.

This invention is in the nature of a modification or refinement of the spouting system for type casting machines disclosed and broadly claimed in my United States Letters Patent No. 1,875,565, issued September 6, 1932.

An object of this invention is to increase the efficiency of the spouting system by a novel arrangement of the several co-operating parts thereof.

20 A further object of the invention is to mount the several parts thereof in convenient and accessible places relative to the machine, whereby they may be quickly and easily installed as attachments.

25 Another object of the invention is to provide a spouting system that can be manufactured at relatively small cost.

These and other objects and advantages of the invention will be fully set forth in the description made in connection with the accompanying drawings.

To the above end, generally stated, the invention consists of the novel construction and arrangement of parts hereinafter described and defined in the claims.

In the accompanying drawings, which illustrate the invention, like characters indicate like parts throughout the several views.

Referring to the drawings:

40 Fig. 1 is a fragmentary front elevation of a type casting machine having the invention embodied therein, some parts being removed and other parts being sectioned;

Fig. 2 is a fragmentary view in left-hand elevation;

Fig. 3 is a fragmentary view partly in elevation and partly in section taken substantially on the line 3—3 of Fig. 1;

Fig. 4 is a fragmentary view partly in plan and partly in section, taken substantially on the line 4—4 of Fig. 1, with some parts removed and other parts shown by means of broken lines;

Fig. 5 is a fragmentary view partly in elevation and partly in section taken substantially on the line 5—5 of Fig. 1;

Fig. 6 is a rear elevation of the bracket and attached apron;

Fig. 7 is a fragmentary detail view showing the mold disc and the rear trimming knife;

Fig. 8 is a fragmentary detail view showing the front trimming knife and deflector attached to the vise frame;

Fig. 9 is a fragmentary detail view in section showing the front trimming knives and aligned mold;

Fig. 10 is a fragmentary view partly in front elevation and partly in section taken on the line 10—10 of Fig. 2; and

Fig. 11 is a fragmentary detail view principally in section taken on the line 11—11 of Fig. 10.

Of the parts of the type casting machine illustrated for the purpose of showing the invention applied thereto in working position, it is important to note the main frame 12, ring gear 20 equipped mold disc 13 journaled to the slide 14 on said main frame, driven pinion 15 meshing with said ring gear, mold pockets 16 in the mold disc 13, molds 17 in certain of said pockets, rear trimming knives 18 mounted on the slide 14 for trimming the bottoms of type bars, not shown, in the molds 17 under rotation of the mold disc 13, justification levers 19 on the main frame 12, which extend transversely of the mold disc 13 and are spaced therebelow, melting pot 20 having a pair of depending legs 21 pivoted on a horizontal shaft 22 journaled on the main frame 12 below the mold disc 13 and extending parallel to the plane thereof, vise frame 23 pivoted on the shaft 22 between the legs 21 for outward swinging movement, front trimming knives 24 mounted on said vise frame, and wiper blade 25 for the front trimming knives 24. It will be noted by reference to Fig. 3, that the mold disc 13 has on its perimeter a rearwardly projecting annular flange.

Referring now in detail to the invention, to wit: the spouting system, the numeral 26 indicates a scoop-like receptacle having an open top, a front handle 27 and a transverse handle 28 secured to and between the sides of said receptacle. The receptacle 26 is held suspended above the floor line α by a hanger 29 which extends transversely under a low member 12', forming a part of the left hand side of the frame 12. Forming a part of the hanger 29 is an upstanding transverse flange 30 which extends parallel to the outer face of the frame member 12' and is detachably secured thereto by a screw 31, see Fig. 2. This hanger 29 further includes a pair

10

25

30

35

40

45

50

55

of wide side members 32, the lower edges of which are turned horizontally inward to afford a pair of guide rails 33 on which the receptacle 26 is slidably mounted and has a working fit between said side members.

It will be noted that the receptacle 26 extends transversely of the machine so that the same may be removed from the hanger 29 at the left-hand side of the machine and emptied to remove waste metal therein, without disturbing an operator of the machine sitting in front thereof. It will also be noted that the receptacle 26 extends longitudinally under the mold disc 13 and its driving pinion 15, with its longitudinal center substantially directly under the frame member 12'. The top of the hanger 29, outward of the frame member 12', affords a cover for the underlying portion of the receptacle 26, leaving the rear portion of said receptacle open for the precipitation of waste metal therein.

A channel-like trough or chute 34 extends circumferentially under the mold disc 13 above the justification levers 19 and in the paths of movement thereof. This chute 34, at its right-hand end, is detachably secured to a bracket 35 by a separable hinge 36 comprising a horizontal transverse pin 37 on the chute 34 and a segmental socket 38 in the bracket 35. Said pin 37 is free for endwise removal from the socket 38 by an outward lateral movement of the chute 34. A stop lug 39 on the hinge pin 37 normally engages a shoulder 40 on the bracket 35 and holds the chute 34 in a forward and downward inclined position with its free end positioned over the receptacle 26. The outer side of the chute 34 extends above the under side of the mold disc 13, and the inner side thereof is upward and outward inclined and of such height as to freely pass under said mold disc during the removal of the chute 34 from the bracket 35. Said chute 34, at the free end portion of its bottom member, is bent abruptly downward to afford a lip 41, which directs waste metal from the chute 34 downward into the receptacle 26 at substantially the center thereof.

The purpose of removably mounting the chute 34 is to permit the mold disc 13 to be moved forward by its slide 14 and out of mesh with the pinion 15, and expose the back of said disc or parts normally covered thereby.

Formed with the bracket 35 is an upward and rearward inclined apron 42 which forms a rear extension of the bottom member of the chute 34, and its outer end is substantially at the right-hand extremity of the mold disc 13.

Detachably secured to the vise frame 23, directly below the front trimming knives 24, is a deflector 43 having on its right edge a perpendicular flange 44. When the vise frame 23 is closed, the lower end of the deflector 43 overlies the adjacent portion of the chute 34 and its flange 44, which is downwardly inclined to the left, and directs waste metal onto the apron 42 and chute 34.

A wide apron 45 is detachably secured by screws to the legs 21 and is curved downward from the under side of the melting pot 20 to a point in which it overlies the chute 34, at the back of the mold disc 13 and the rear end portion of the receptacle 26. Said apron 45, between the legs, is made transversely convex to draw waste metal precipitated thereon to a central point and discharge the same into the chute 34. This apron 45 also extends between

the left-hand leg 21 and adjacent side of the frame 12 and overlies the receptacle 26.

The improved spouting system further includes an upright channel-shaped spout 46 arranged to discharge into the receptacle 26. This spout 46 is substantially transversely and centrally aligned relative to the plane of the mold disc 13, its sides are turned toward said disc and its back is substantially directly below the intermeshing teeth of the ring gear on the mold disc 13 and the pinion 15. Said spout 46, at the lower end portion of its back, bears against the inner face of the frame member 12'. To facilitate the mounting of the spout 46 on the machine, the same is made in two longitudinal sections 47 and 48, the back members of which overlap. The spout section 47 is detachably secured at its upper end to the frame 12 by an angle bracket 49, one flange of which is permanently secured to said section and the other flange of which is detachably secured to the frame 12 by a screw 50 which extends through a notch in said section. To remove the spout section 47 from the frame 12, it is only necessary to loosen the screw 50 and move said section downward to withdraw the bracket 49 therefrom. The lower end portion of the spout section 47 loosely extends between the bearing on the frame member 12' for the shaft 22 and an arm 19' on the left-hand justification lever 19, and is thereby held against transverse pivotal movement on the screw 50.

The spout section 48 at its lower end, rests on the adjacent bearing for the shaft 22 and around which it is fitted. Said spout section 48, at its upper end, is extended upward and outward to afford a deflecting flange 51 which underlies the pinion 15. The spout member 48 is carried by a hopper 52 removably mounted on the hanger 29. Said hopper 52 has a vertical back member with which the side member of the spout section 48 has flat engagement and is rigidly secured thereto by rivets 53. The bottom of the hopper 52 is upward and outward inclined from the lower end of its back and the sides of said hopper are parallel.

Formed in the top of the hanger 29, forward of the front end of the frame member 12', is an aperture into which the V-shaped lower end portion of the hopper 52 is fitted. The upper end portion of the front hanger side members 32 is turned outward to afford a supporting flange 54 on which the hopper 52 rests and is detachably secured thereto by a thumb-nut-equipped screw 55, which extends through aligned holes in said flange and the bottom member of said hopper. Formed in the back member of the hopper 52, at the bottom thereof, is an opening 56 which leads from said hopper to the receptacle 26.

The back member of the hopper 52 extends to the top of the spout 46 and materially outward of the right-hand side member of said hopper, to afford a baffle 57.

By reference to Fig. 2, it will be noted that the right-hand side member of the hopper 52 is extended below the bottom of said hopper to afford a retaining member 58, for a purpose which will presently appear. The outer side member of the chute 34 is notched just above its lip 41, see Fig. 1, and the overlying portion of said member is outwardly offset to receive the adjacent edge portion of the baffle 57 and thereby hold said chute 34 against outward lat-

eral movement that would tend to separate its hinge 36.

Discarded type bars and other waste metal may be dropped into the hopper 52 and conveyed thereby to the receptacle 26. The hopper 52 is also well adapted to receive dust and waste metal cut from type bars by a saw attachment applied to the type casting machine. For the purpose of this case, it is not thought necessary to illustrate a type bar sawing attachment, and hence only its discharge spout 59, into which dust and waste metal cut from type bars are precipitated, is shown. This spout 59 is narrow, deep and mounted on the vise frame 23 outward thereof, and is downward inclined toward the hopper 52. Said spout 59 is detachably secured at its upper end, by a screw 60, to the vise frame 23, and at its secured lower end by a hook and loop 61, see Figs. 2 and 10.

20 The front end of the spout 59 is parallel to the adjacent sides of the hopper 52 and spaced therefrom to permit the required opening and closing movements of the vise frame 23 in which it swings on the shaft 22.

25 Pivoted to the lower end of the spout 59 is a short auxiliary spout 62 which extends into the hopper 52 through a notch 63 in the right-hand side member of said hopper. During the initial opening movement of the vise frame 23, in which the same swings downward, the auxiliary spout 62 engages the lower edge of the notch 63 and further downward movement of the vise frame 23 will fold said auxiliary spout, as shown in Fig. 11, so that the same will slide on the respective side member of the hopper 52 and its retaining member 58.

The lower end of the spout 59 is normally closed by a gravity-closed gate 64 hinged at its upper end to the sides of the spout 59. On the outer 40 face of the gate 64 is a finger 65 that is overlapped by the auxiliary spout 62 when in an inoperative position, and holds the gate 64 closed during the opening and closing of the vise frame 23, so that in case there is any waste metal in the 45 spout 59, it will be held thereby by the gate 64 until said vise frame is returned to its closed position, and at which time the auxiliary spout 62 will drop by gravity into its operative position and release the gate 64. This locking of the gate 64, 50 while the vise frame 23 is open, prevents waste metal in the spout 59 from being spilled on the floor.

From the above description, it is evident that a squirt of molten metal back of the mold disc 34, 55 during a casting operation, or a splash of molten metal from the melting pot 20, together with shavings cut from a type bar by the rear trimming knife 18, will be precipitated onto the aprons 42—45 into the chute 34 and conveyed 60 thereby into the receptacle 26, or precipitated directly into said receptacle. Any flying pieces of metal, at the left-hand side of the mold disc 13, from the rear trimming knife 18 or other parts of the machine, will be intercepted by the 65 trough 46 or the baffle 51 and precipitated into the receptacle 26.

A squirt of molten metal, at the front of the mold disc 13, during a casting operation, or shavings cut from a type bar by the front trimming 70 knives 24 which drop therefrom or that are removed therefrom by the knife wiper 25, will be directed by the deflector 43 and its flange 44 onto the apron 42 and into the chute 34 where the same is conveyed to the receptacle 26.

75 During the upward movements of the justifica-

tion levers 19, the right-hand lever 19 engages the chute 34 first, and thereafter said chute is engaged by the left-hand lever which carries the same out of the paths of movement of both of said levers. The engagement of the chute 34 by 55 the justification levers 19 shake said chute and thereby accelerate the flow of waste metal therefrom.

Dust and waste metal from the sawing attachment dropped into the spout 59 will be delivered 10 thereby over the auxiliary spout 62, into the hopper 52 where the same will be precipitated into the receptacle.

From a broad viewpoint, the chute 34 may be termed a "receptacle" and the hopper a "spout". 15

Obviously, the improved spouting system may be very quickly and easily mounted on a type casting machine without interfering with any of the movable parts thereof or without cutting or otherwise changing the machine. 20

From the foregoing, it will be understood that the structures described above are capable of modifications within the spirit of the invention disclosed and claimed.

What I claim is:

1. The combination, in a type casting machine having a vise frame mounted for opening and closing movement, and a spout for a type bar sawing device mounted on said frame, of a receptacle, a conduit arranged to discharge into 30 the receptacle, said spout having a movable auxiliary spout arranged to discharge into the conduit, and means for moving the auxiliary spout into an inoperative position during movement of the vise frame. 35

2. The combination, in a type casting machine having a vise frame mounted for opening and closing movement, and a spout for a type bar sawing device mounted on said frame and having a gate normally closing the spout, of a receptacle on the machine, a conduit arranged to discharge into the receptacle, said spout having a movable auxiliary spout arranged to discharge into the conduit, and means for moving the auxiliary spout into an inoperative position during 45 movement of the vise frame and into a position to hold the gate closed. 40

3. The combination, in a type casting machine having a vise frame mounted for opening and closing movements, and a spout for a type bar sawing device mounted on the vise frame, of a receptacle, a conduit arranged to discharge into the receptacle, said spout having a gravity closed gate and a gravity closed auxiliary spout, the latter overlying the spout, arranged to discharge 50 therein and be moved into an inoperative position, by engaging the conduit during the opening of the vise frame, in which it holds the gate closed. 55

4. The combination, in a type casting machine having a mold disc, and a justification lever, of a channel-like chute extending circumferentially under the mold disc and transversely over the justification lever in its path of movement, a bracket to which the chute is pivoted for raising and lowering movements, a fixed apron on the bracket arranged to discharge into the chute at the receiving end thereof, and means independent of the chute for conveying waste metal, produced during the formation of a type bar, transversely 70 of the chute and apron and deliver the same therein, said chute being separable from the bracket by a lateral movement, and means normally holding the chute against separation from said bracket. 75

5. The combination, in a type casting machine having a mold disc, a vise frame, trimming knives on the vise frame, and a justification lever, of a channel-like chute extending circumferentially under the mold disc and transversely over the justification lever in its path of movement, a bracket to which the chute is pivoted for raising and lowering movements, a fixed apron on the bracket arranged to discharge into the chute at the receiving end thereof, means on the vise frame normally overlapping the apron for conveying waste metal, produced in the formation of a type bar, transversely of the chute and apron and deliver the same therein, said chute being separable from the bracket by a lateral movement, and means normally holding the chute against separation from said bracket.

6. The combination, in a type casting machine having a vise frame mounted for opening and closing movements, and a spout for a type bar sawing device mounted on the vise frame, of a receptacle having a member normally overlapped by the spout and one of which member or spout, is movable to permit the spout to pass said member during the opening and closing of the vise frame.

7. The combination with a type casting machine having a rotatable disc, said disc having on its back an annular flange and also having within said flange a mold, a pivoted leg structure at the back of the disc, and a melting pot carried by the leg structure for movement thereby into and out of casting position with the mold, of a chute extending circumferentially under the disc, and an apron carried by the leg structure and held downwardly inclined toward the disc with its lower edge extending over the chute and substantially parallel to the back of the disc, whereby waste metal from the mold and the melting pot, caught on the internal surface of said flange and carried upwardly thereby during the rotation of the disc, will be precipitated on to the apron and discharged therefrom into the chute.

8. The combination with a type casting ma-

chine having a rotatable disc, said disc having on its back an annular flange and also having within said flange a mold, a pivoted leg structure at the back of the disc, and a melting pot carried by the leg structure for movement thereby into and out of casting position with the mold, of a chute extending circumferentially under the disc, an open receptacle at the discharge end of the chute, and an apron carried by the leg structure and held thereby downwardly inclined toward the disc with its lower edge extending substantially parallel to the back of the disc and over the chute and the apron receptacle, whereby waste metal from the mold and the melting, caught on the internal surface of the flange and carried upwardly thereby during the rotation of the disc, will be precipitated onto the apron and discharged therefrom into the chute and the open receptacle.

9. The combination with a type casting machine having a rotatable disc, a vise frame, and trimming knives carried by the vise frame, of a chute extending circumferentially under the mold disc, and a deflector carried by the vise frame and held thereby, when closed, in overlapping arrangement with the chute at its receiving end position and arranged to convey waste metal from the trimming knives circumferentially of the mold disc and discharge the same from the chute.

10. The combination with a type casting machine having a rotatable disc provided with a mold, of a chute extending circumferentially under the disc, an open receptacle at the receiving end of the chute, an apron mounted on said machine and held thereby downwardly inclined toward the disc with its lower edge extending over the chute and open receptacle and substantially parallel to the plane of the disc, whereby waste metal produced during the formation of a type bar will be precipitated onto the apron and discharged therefrom into the chute and open receptacle.
